UNITED STATES PATENT OFFICE.

GEORGE D. HOOP, OF JACKSON, OHIO.

LIGHTNING-ARRESTER.

SPECIFICATION forming part of Letters Patent No. 436,238, dated September 9, 1890.

Application filed July 7, 1890. Serial No. 357,964. (No model.)

To all whom it may concern:

Be it known that I, GEORGE D. HOOP, of Jackson, in the county of Jackson and State of Ohio, have invented a new and Improved 5 Lightning-Arrester, of which the following is a specification, reference being had to the annexed drawings, forming a part thereof, in which—

Figure 1 is a front elevation of my improved lightning-arrester, and Fig. 2 is a longitudinal section taken on line 22 in Fig. 1.

Similar letters of reference indicate corresponding parts in both views.

The object of my invention is to provide a 15 simple and efficient arrester for attachment to dynamo-circuits, more especially for use in connection with the electric-lighting circuits.

My invention consists in the construction and arrangement of parts hereinafter described and claimed.

To the insulated base-piece A are attached the metallic plates $a a' a^2$. The said plates are provided with binding-screws $b b' b^2$ for receiving the wires $c c' c^2$, communicating 25 with the circuits to be protected. A plate B, provided with apertures $d d' d^2$, is secured to the base-piece A, and in these apertures are arranged serrated disks $e e' e^2$, with their points equally distant from but not touching 30 the plate B. The serrated disks are provided at their centers with contact-buttons $f f' f^2$, which receive the fusible wires $g g' g^2$, communicating with the plates $a a' a^2$.

To a plate C, secured to the base-piece A, 35 parallel to the plate B, are pivoted the switch-arms $h h' h^2$, which are connected by an insulating-bar i , by means of which the said switch-arms may be moved so as to bring them into contact with the contact-buttons $f f' f^2$, or with the contact-buttons $j j' j^2$, projecting from the apertured plate B.

To the plate C are attached binding-posts D D' for receiving the ground-wires E E'.

While the circuits are charged with the 45 current from the dynamos, the switch-arms $h h' h^2$ are allowed to rest upon the contact-buttons $j j' j^2$. If either circuit is struck by lightning while in operation, (the one connected with the wire c , for example,) the 50 charge passes to the plate a , thence to the serrated disk e through the wire g . Leaping across the space between the serrated disk and the plate B, it passes over the plate B, over the switch-arms $h h' h^2$ to the plate C, 55 thence through the ground-wires E E' to the

ground. When the circuits are not in use, the switch-arms $h h' h^2$ are moved so as to bring them into contact with the buttons $f f' f^2$, thus establishing a direct metallic communication between the wires $c c' c^2$ and the ground-wires E E'. The charge then passes directly to the switch-arms without leaping across the space between the serrated disks and the plate B. If while the switch-arms are arranged as last described the dynamos 65 are inserted, the grounding of the circuits is prevented by the melting of the safety-wire belonging to the circuit. A melted safety-wire is readily replaced by a new one.

By employing the serrated disks and the 70 apertured plate B a large number of discharge-points are provided for the escape of lightning from the circuits to the ground without danger of grounding the circuits.

Having thus described my invention, I 75 claim as new and desire to secure by Letters Patent—

1. In a lightning-arrester, the combination, with an insulated serrated disk having a fusible line-wire connection and a contact-point, of an insulated plate having an aperture receiving the said disk and a contact-point, and a switch having a ground-connection and adapted to swing from one of said contact-points to the other, substantially as 85 described.

2. In a lightning-arrester, the combination of an insulating base-piece A, a metallic plate a , a serrated disk e , a fusible wire g , connecting the plate a and serrated disk e , 90 an apertured plate B, surrounding the serrated disk e , and a switch h for making direct connection between the plate B and the ground or the serrated disk e and the ground, substantially as specified. 95

3. A lightning-arrester, comprising the base A of insulating material, the plates $a a' a^2$ thereon, provided with line-wire connections, the plate B, having a series of apertures and contact-points $j j' j^2$, the serrated disks $e e' e^2$ within said apertures and provided with contact-points $f f' f^2$, fusible wires connecting plates $a a' a^2$ with the said disks, the grounded plate C, having three switches $h h' h^2$, and a connecting-bar i to operate them 105 simultaneously, substantially as described.

GEORGE D. HOOP.
